JOSEPH ZUBATY, OF FLINT, MICHIGAN, ASSIGNOR TO A C SPARK PLUG COMPANY, OF FLINT, MICHIGAN, A COMPANY OF MICHIGAN

ODOMETER

Application filed June 18, 1928. Serial No. 236,362.

My invention relates to an improved odometer mechanism such as is used in speedometers for motor vehicles. Such odometers usually consist of a plurality of figure wheels 5 arranged side by side on a supporting shaft.

An object of the invention is to improve the alignment of the figures of the figure wheels.

Other objects and advantages will be apparent upon referring to the specification and accompanying drawing, in which—

Fig. 1 is a perspective view of the odometer figure wheels, showing my improved means for holding the wheels in correct alignment;

Fig. 2 is a sectional view, taken on the line 2—2 of Fig. 3 of one of the figure wheels, showing part of the mechanism employed for holding the wheels in alignment;

Fig. 3 is a front elevation of the figure wheels, showing how they appear when held in proper alignment by my improved mechanism; and

Fig. 4 is a view similar to Fig. 3, but showing how the figure wheels sometimes appear 25 without my improved mechanism.

The reference numeral 10 indicates a speedometer frame in which is supported a shaft 12. Mounted upon this shaft are figure wheels 14, 16 and 18, which are used to register the trip mileage in a well known manner. The figure wheel 14 is driven in any suitable manner from the speedometer driving mechanism, and is provided at its left hand side with transfer teeth like teeth 20 and 21 on 30 wheel 16 as shown in Fig. 2. Rotatably supported on a second shaft 22 are transfer pinions 24 which serve to transmit the motion from one figure wheel to the next.

40 The figure wheels 16 and 18 have on their right hand side gear teeth 26 which register with teeth 28 on the transfer pinions 24. The opposite side of the latter have formed on them narrow teeth 30 and broad teeth 32, alternately spaced. A ledge 34 is formed on 45 the left hand side of the figure wheels 14 and 16. Normally the broad teeth 32 of the transfer pinions 24 bear against this ledge for the purpose of preventing rotation of the transfer pinions, which would cause the next

figure wheel to be rotated, thus allowing the figures to get out of line.

Each time the figure wheel 14 makes a complete revolution one of the narrow teeth 30 is engaged by one of the transfer teeth 55 20 and 21, which causes the pinion to be partially rotated. The ledge 34 is interrupted between the transfer teeth 20 and 21 so that a broad tooth 32 may be turned down in between the transfer teeth 20, 21. Since the 60 transfer pinion is always in mesh with gear 26 of figure wheel 16, this movement of the transfer pinion causes the figure wheel 16 to be rotated sufficiently to bring the next figure into view. In a like manner each time the 65 figure wheel 16 is turned one complete revolution the transfer pinion between it and the figure wheel 18 causes the latter to be turned a tenth of a revolution.

It will thus be seen that normally the transfer pinions and the figure wheels are prevented from turning by the teeth 32 of the pinions engaging the ledge 34 on the figure wheels, but since there necessarily must be one point on each figure wheel where the 70 ledge is interrupted to permit the teeth 32 to mesh with the transfer teeth 20, 21 the transfer pinion is only held a one side at this point. Due to the vibration of the vehicle, there is a tendency for the figure wheels to change their 75 position, and since they are only held from turning in one direction at this point, they are apt to move slightly in the opposite direction. This tendency to move takes place when the figure wheels are in a position so that the figures "zero" appear through the opening in 80 the speedometer face plate.

Naturally when the speedometer is placed on the vehicle when the latter is assembled at the factory, all of the figure wheels are at 90 "zero" position. If some means is not provided to prevent this movement, the figure wheels tend to assume a position such as is shown in Fig. 4, which is very objectionable since it detracts from the appearance of the 95 speedometer. I have overcome this difficulty by forming a weighted portion 36, on each figure wheel, which throws the wheel out of balance slightly. This weight is so located 100 that it will tend to rotate its wheel counter-

clockwise for the zero reading position of the wheel as shown by the drawing. The weight then tends to rotate its wheel and, through the engagement of the teeth of the 5 wheel with the transfer pinion, to hold one of the teeth of the latter on the ledge 34. In other words, when the figure wheels are in "zero" or transfer position, they are free to move a slight amount in a clockwise direction, 10 as viewed in Fig. 1, and the unbalancing action of the weighted portion 36 tends to rotate the figure wheels in a counterclockwise direction to counteract this.

It will be readily seen that this device will 15 prevent the figure wheels from turning due to vibration when they are in the "zero" or transfer position, thus keeping the figures in correct alignment. It is only necessary to prevent this movement at one point, which is 20 where the ledge 34 is interrupted between the transfer teeth 20 and 21, since the engagement of the teeth 32 with the ledge 34 prevents rotation at all other times.

It is thought from the foregoing, taken in connection with the accompanying drawing, that the construction and operation of the device will be apparent to those skilled in the art, and that various changes in size, shape and proportion and details of construction may be made without departing from the spirit and scope of the appended claim.

I claim:

Odometer mechanism comprising in combination a plurality of axially aligned figure wheels, transfer means between two of said wheels to drive a second from a first, weight means to unbalance said second wheel of said pair, said weight means operable at zero position of said figure wheels through the instrumentality of said transfer means to aid in maintaining alignment of the zeros on said figure wheels.
